CONRAD JOBST, OF TOLEDO, OHIO, ASSIGNOR TO THE TOLEDO AUTOMATIC BRUSH MACHINE COMPANY, OF TOLEDO, OHIO, A CORPORATION OF OHIO.

UNIVERSAL BRUSH MACHINE.

Application filed February 19, 1925. Serial No. 10,291.

The invention relates to brush machines of that type in which brush backs previously bored either in the same or a different machine are carried by an intermittently movable work holder through a cycle successively registering all of the holes of the pattern with the tuft setting mechanism. With such machines it is essential that the movement in each cycle should be an exact repetition of those in previous cycles, so that each brush back will have all of its holes filled with tufts. Consequently, whenever a new pattern is used, considerable adjustment is required. Moreover, brushes vary not only in the pattern of the tufts and the number of holes in the pattern, but also as to the angles at which the tufts are set, so that a machine designed for making one type of brush is not adapted for the manufacture of another type. It is the object of the present invention to obtain a construction of machine which is capable of being quickly adjusted for the manufacture of various types of brushes, as well as brushes having a varying number of tufts and in various patterns. To this end the invention consists in various features as hereinafter set forth.

In the drawings:

Figure 1 is a side elevation of the upper portion of the machine;

Figure 2 is an elevation viewed from the opposite side of the machine;

Figure 3 is a plan view;

Figure 4 is a vertical longitudinal section;

Figure 5 is a section on line 5-5 of Fig. 2;

Figure 6 is a section on line 6-6 of Fig. 2;

Figure 7 is an elevation of the variable speed driving mechanism;

Figure 8 is a detailed view of the stop mechanism;

Figure 9 is a detailed view of the wire feed mechanism;

Figure 10 is a detailed view of the upper wire feed tube;

Figure 11 is a wiring diagram of the electrical mechanism.

The tuft forming and setting mechanism may be of any suitable construction, but preferably is of the type forming the subject matter of my co-pending application Serial No. 527,590, filed January 7, 1922, and comprising a bristle holding magazine 1 having a tapering forward end 2 from which the

tufts are successively picked and transferred to a nozzle 3 reciprocated by the pitman rod 4 and crank 5 towards and from the brush back holder 6. There is also a wire feeding mechanism 7 for a staple forming and driving mechanism (not shown) associated with the reciprocating nozzle, the construction being such that each time the nozzle is advanced into registration with the hole in the brush back a tuft is ejected therefrom into said hole and the securing staple driven into engagement with the back. Where the tufts are set in angular relation to each other, it is usual to drill the brush backs and set the tufts therein in the same machine. To this end I have arranged parallel to the tuft forming and setting mechanism a drilling mechanism having the rotary spindle 8, which is reciprocated by a cam or eccentric 9 mounted on the shaft 10. This shaft also carries the crank 5 for actuating the nozzle reciprocating pitman 4 and an eccentric 11 for actuating the staple driving pitman 12, the parts being so timed that each time the nozzle is advanced towards the work holder 6, the spindle 8 is similarly advanced towards a work holder 6^a for the brush back to be bored.

The work holders 6 and 6^a are simultaneously and correspondingly adjusted during the portion of the cycle in which the nozzle and drill spindle are withdrawn therefrom, but are stationary during the drilling and tuft setting operations. In machines of this type it is usual to actuate these work holders by cams which are mounted on a shaft operated in definitely timed relation to the operation of the tuft setting and drilling mechanism. Each change in brush pattern requires a change in these cams, but whatever cam is used, the cycle must be completed in one full revolution of the cam shaft. Thus where a brush has a large number of tufts the angular movement of the cam for each adjustment of the holder is comparatively small, whereas in a brush that has only a small number of tufts the angular movement will be relatively large. Consequently it is not desirable to greatly vary the number of tufts in any one machine and it is usual to provide separate machines for brushes differing materially from each other.

As has been stated, it is one of the objects of the present invention to obtain a machine

having a wide range of adjustment both as to the number of tufts, the character of the pattern and the angular relation of the tufts with each other. To this end, instead of the usual fixed timed relation between the tuft setting mechanism and cam shaft, there is provision whereby the same angular movement of the cam may be used for each movement of the work holder regardless of the total number of tufts in the brush. As this would result in an incomplete revolution of the cam shaft for less than the maximum number of tufts, further provision is made for completing the cycle subsequent to the setting of the last tuft in the brush while the tuft setting and drilling mechanism is stationary. This consists in means for disconnecting the cam carrier from its driving train after the stopping of the tuft setting mechanism, driving said carrier by an independent motor to complete its cycle and then reengaging with the normal drive train to be again in fixed timed relation to said tuft setting mechanism, the construction being as follows:

The shaft 10 is driven by an electric motor 13 through the medium of a step-down gear train consisting of the pinion 14 on the motor shaft and the large gear wheel 15 on the shaft 10. At the end of the shaft 10 are the intermeshing bevel gear wheels 16 and 17, the latter driving the intermeshing spur gears 18 and 19. The gear 19 is of annular form and is rotatively mounted on a circular bearing 20, in which is eccentrically journaled the shaft 21 having a crank arm 22. This crank arm is connected by a pivotal link 23 with the annular gear 19, so that during each revolution of said gear the shaft 21 will also complete a revolution, but at variable speeds. The shaft 21 is connected by the bevel gear wheels 24 and 25 with a vertical shaft 26 having at its lower end the worm 27 normally in mesh with the worm gear 28. This worm gear is mounted on a horizontal shaft 29 for the cam carrying drum 30, the cams of which, through mechanism to be hereinafter described, actuate the work holders 6 and 6^a.

With the mechanism thus far described, it is obvious that each complete revolution of the worm wheel 28 will correspond to an exact number of cycles of the tuft setting mechanism, this determining the maximum number of tufts that can be placed in any one brush. Where, however, the brush operated upon has less than this maximum number of tufts, the worm wheel 28 and drum 30 will not complete their cycle and it is necessary to stop the machine at such point. Thus if the machine were again set in motion, the next cycle would not be an exact repetition of the first. This difficulty is overcome through the provision, previously referred to, for arresting movement of

the tuft setting mechanism and then independently revolving the cam carrying drum to complete its cycle, the detailed construction being as follows:

The worm wheel 28, or some other member revolving with the shaft 29, is provided with an adjustable pin 31, preferably engaging any one of a series of sockets 32, which are spaced to correspond in number to the cycles of the tuft setting mechanism. This pin is adapted to engage and operate a lever 33 which actuates two electric switches 34 and 35 to respectively open and close the same. The switch 34 controls the energizing circuit of the motor 13 and also that of an electro-magnet 13^a, which latter, when de-energized, permits the operation of a brake 13^b for quickly arresting movement of the motor. The switch 35 controls the energizing circuit of a second motor 36, which, through the medium of the pinion 37, gear wheel 38, pinion 39 and gear wheel 40, continues the rotation of the worm wheel 28 and drum 30. However, before this movement can be effected, the driving train from the motor 13 must be disconnected, which is preferably accomplished by withdrawing the worm 27 from mesh with the worm wheel 28. To this end the switch 35, when closed, also energizes a solenoid or electro-magnet 41, which operates a toggle lever 42 connected with the bearing 43 for the lower end of the worm shaft 26, the upper end of said shaft being journaled in a pivotal bearing 44. Thus, occurring simultaneously with the deenergizing of the motor 13, the stopping of the tuft setting mechanism and the energizing of the motor 36, the solenoid 41, acting through the toggle levers 42, will withdraw the worm 27 from engagement with the worm gear 28, permitting the free movement of the latter. It is therefore apparent that the setting of the pin 31 determines the point at which the tuft setting mechanism is stopped, but that the worm wheel 28 and cam drum 30 continue to rotate under the actuation of the motor 36.

To stop the rotation of the cam drum, a second pin 45 in fixed position on the worm wheel 28 engages a lever 33^a for operating a circuit breaking switch 35^a. This switch breaks the circuits of the motor 36 and solenoid 41 to stop the rotation of the worm wheel and to permit the reengagement of the worm therewith, but it is absolutely essential, first, that the cycle of the cam should be exactly completed, and second, that the worm should reengage with the worm wheel in the same timed relation as that before disengagement, which is accomplished as follows:

The opening of the switch 35^a occurs before the completion of the cycle of the cam drum, which, however, continues to rotate by its own momentum after the motor 36 is de-

- energized. To prevent the reengagement of the worm with the worm wheel before completion of movement of the latter, there is arranged upon the bearing 43 a finger 43^a, which 5 extends into engagement with a slide 47 arranged in bearings 47^a adjacent to the worm wheel. The slide 47 is yieldingly actuated by a spring 47^b so as to follow the outward movement of the bearing 43 and finger 43^a, 10 in which projected position it stands in the path of a stop lug 46 on the worm wheel 28. The worm wheel is also provided with a cam flange 46^a, which engages the inner end of the slide 47 in advance of the deenergizing 15 of the solenoid 41 and holds said slide together with the finger 43^a and bearing 43 from movement until the cycle of the cam drum is completed. A spring 49 operating counter to the pull of the solenoid 41 tends 20 to restore the toggle levers 42 to normal position and to thereby force the worm into engagement with the worm wheel, but such movement is prevented as long as the flange 46^a is in engagement with the slide 47, so 25 that while the solenoid is deenergized in advance of the completion of the cycle, the worm wheel is still held from reengagement until the cycle is completed and the stop 46 contacting with the projecting portion of 30 the slide 47 arrests further movement of the cam wheel. As it is impossible to so time the parts that the inertia of the motor 36 will be overcome at the same instant that the stop 46 engages the slide 47 and as 35 there might be danger of breaking of the parts through the continued torque of the motor, a friction clutch 48 is preferably arranged between the gear wheel 38 and the pinion 39. This may be of any suitable construction, but as shown in Figure 6, consists of spring pressed friction shoes 48^a arranged in the hub of the gear wheel 38 and cooperating with associated parts to supply the necessary friction torque. This is limited to avoid any overstressing of parts when 45 the stop 46 engages the slide 47, but is sufficient to hold said slide from movement until all motion of the motor 36 is arrested. Thus while the flange 46^a is withdrawn from 50 the path of the slide 47 at the same time that the lug 46 engages said slide, the friction produced by the torque of the motor while still running holds the slide 47 from movement, so that the reengagement of the 55 worm with the worm wheel is exactly timed.
- The cams on the drum 30 must be changed for each brush differing either in number of tufts or the arrangement thereof, and to facilitate such changes a series of different 60 cams may be mounted upon the drum. These are alternatively placed in operative relation with the work holder actuating mechanism by adjustment of the drum longitudinally upon the shaft 29. As shown, the shaft 65 29 has a tubular portion within which is arranged an adjusting screw 50 operable from the end of the shaft. This screw engages a nut 51, which passes through a longitudinal slot 52 in the shaft and engages the hub of the drum. Thus the drum is rotatively coupled with the shaft but may be adjusted longitudinally thereon to bring the selected cams into operative relation to the work holder actuating mechanism.
- The construction of work holders varies 70 according to the particular type of brush to be manufactured and to enlarge the scope of the machine, exchangeable work holder units are provided. These units are arranged in pairs in operative relation respectively to the tuft setting and drilling mechanism, both being mounted on a base 80 53, which is detachably secured to the main frame 54 of the machine. At least two types of holders are used as exchangeable units, the one designed to set the tufts parallel to each other and the other in angular relation. Either of these units may be mounted on the frame and by adjusting the proper cams in relation thereto may be successfully 85 operated without other change in the machine.
- The unit for setting tufts in angular relation such as is common practice with hair brushes is of the following construction: 90 The base 53 is provided with swivel bearings 55 for the bifurcated heads 56, the latter having parallel cheek plates 57, which embrace a member 58. This member 58 is pivoted upon a cross pin 59 carried by a 100 slide 60 horizontally movable in the cheek plates 57, while springs 61 engaging said slide yieldably press the same in a rearward direction or away from the tuft setting mechanism or drill spindle. The forward 105 end of the member 58 is provided with slide-ways 62 for receiving exchangeable work holding heads 63 upon which the brush backs are clamped. In rear of the member 58 is a post 64 mounted on the base 53 and carrying at its upper end a horizontally adjustable finger 65, preferably having a threaded engagement with said post. This finger 65 is adapted to bear against a pattern face 66 which is exchangeably secured 110 to the rear end of the member 58 by bolts 67. The pattern is so fashioned as to maintain the brush back clamped in the head 63 a uniform distance from the tuft setting or 115 drilling mechanism in whatever angular position said head may be adjusted. It is possible, however, to vary such distance by an adjustment of the finger 65, thereby changing the distance of the brush back from the axis of the swivel head 56 and correspondingly altering the amplitude of movement. Thus where various shapes of brush backs are operated upon, the pattern 66 may be 120 selected for the particular back and quickly mounted upon the member 58.
- 125 130 135

The movements of the work holder about the axis of the swivel head 56 and the pivot of the rocking member 58 are respectively effected by separate cams on the drum 30, which cams 68 and 69 are mounted in adjacent pairs upon said drum. These movements are effected in substantially the same manner as described in detail in my copending application Serial #527,591 filed January 7, 1922. These cams peripherally engage rollers 70 on vertical slides 71 and 72 mounted in bearings 73 depending from the base 53. The slide 71 actuates spiral racks 74, which are in mesh with spiral gear segments 75 on the swivel heads 56, respectively of the tuft setting and drilling work holders. The slide 72 is connected to a cross bar 76 having at its opposite ends the vertical rods 77 passing upward axially through the swivel heads and provided at their upper ends with horizontally slotted bearings 78 for engaging a cross pin 79 on the member 58. Thus whenever the rods 77 are raised or lowered, the members 58 will be rocked upon their pivots and whenever the spiral racks 74 are raised or lowered, the swivel heads 56 will be rotated. The combination of these two movements will produce any desired path of movement of the brush back 30 in the clamping head 63 corresponding to the pattern of tufts to be set in said back.

To facilitate mounting of various shapes and sizes of brush backs in the clamping head 63, these heads are recessed to receive a plastic material, such as plaster of Paris, in which the brush back is set. Thus a firm backing is provided for the brush back which exactly fits the same and the back may be retained by a pair of clamping members 80 on opposite sides thereof.

Operation.

In the complete operation of the machine as thus far described, proper adjustment having been made for the particular work to be performed and brush backs in clamping heads 63 being engaged with the work holders, the machine is started by the operation of a circuit closing switch 81. This energizes the motor 13, which through the pinion 14 and gear 15 revolve the shaft 10, thereby operating both the tuft setting mechanism and the drilling mechanisms. At the same time motion is communicated through the bevel gears 16 and 17, spur gears 18 and 19 and variable speed mechanism, including the link 23 and rock arm 22, to the eccentrically journaled shaft 21, thence through the bevel gears 24 and 25 to the shaft 26 and worm 27 which drives the worm wheel 28, and from the latter through the shaft 29, which rotates the drum 30 and cams 68 and 69 mounted thereon. By reason of the variable speed element in this transmission the movement of the cams is at variable velocity, so that for

a portion of the cycle there is but slight movement and in another portion a much greater movement. This facilitates the imparting of an intermittent movement to the work holders and diminishes the angular movement of the cams during the interval of rest while enlarging the angular movement during the period of movement. Thus the work is held rigidly during the drilling and tuft setting operations and is moved by a gradual acceleration and deceleration between such intervals of rest.

Assuming that the number of tufts to be set is less than the maximum number possible on the machine, the pin 31 is engaged with the proper socket 32. Therefore, in the rotation of the worm wheel 28 when this pin 31 engages the lever 33, it will operate the switches 34 and 35, the one deenergizing the motor 13 and magnet 13^a and the other energizing the motor 36. The brake 13^b is of any suitable construction to be instantaneously applied when the magnet 13^a is deenergized, thereby bringing the driven mechanism to an almost instantaneous stop. As specifically shown in Figure 5, the brake comprises a cone member 82 concentric with the motor shaft having a threaded engagement 83 with a stationary bearing 84 and provided with a lever arm 85 connected to the armature of the magnet 13^a. The motor shaft has a conical sleeve 86 in close proximity to the cone 82 so that a slight movement of the lever arm 85 will move the cone 82 into a frictional engagement with said sleeve. This will produce a very powerful braking effect and thereby bring the driven mechanism to a quick stop.

The closing of the switch 35 also energizes the solenoid 41, which, through the toggle links 42, moves the worm 43 out of mesh with the worm wheel 28, and by withdrawing the finger 43^a, permits the slide 47 to be projected by the spring 47^b into the path of the stop 46. At the same time, the motor 36 being energized, will through the pinion 37, gear wheel 38, pinion 39 and gear 40 continue the rotation of the worm gear 28, shaft 29 and drum 30 and cams 68 and 69 until their cycle is complete. Slightly in advance of the completion of this cycle, the pin 45 engaging the lever 33^a will open the circuit of the motor 36 and solenoid 41, but the flange 46^a, by engaging the slide 47, prevents the engagement of the worm until the stop 46 strikes against said slide, arresting further movement of the worm gear. In this position the flange 46^a is out of the path of the slide 47 and as soon as the torque of the motor operating through the friction clutch 48 is overcome, said slide 47 will move out of the path of the lug 46 and will permit the spring 49 to return the toggle levers 42 and engage the worm with the worm wheel.

After the completion of each cycle the work holding clamps are exchanged to re-

move the tufted brush and to introduce a new brush back, after which the operation is repeated. When it is desired to change to a different brush, the screw 50 may be 5 operated to shift the drum 30, bringing another pair of cams 68 and 69 into operative relation to the rollers 70 of the slides 71 and 72. If necessary, another pattern 66 may be placed on the member 58 and the pin 10 31 is adjusted in position to correspond with the cam. These simple changes are all that are required to put the machine in condition for operating on the new brush.

If a change is to be made in the type of 15 brush, such as one having parallelly arranged tufts instead of angularly arranged tufts, the whole work holding unit may be removed by disengagement of the base 53 and a new suitable unit substituted therefor.

20 Any suitable system of electric circuits may be used in connection with the device previously described, but as shown in Figure 11, the arrangement is as follows: 73, 74 and 75 are the leads of a three-wire electrical 25 service controlled by a switch 76. 77 is an electro-magnetically operated switch having its actuating magnet 78 in a circuit 79, which extends from the lead 75 to the lead 74 and includes a push button circuit closing 30 switch 80, and two electro-magnetically operated switches 81 and 82. The switch 81 is closed when its actuating magnet 83 is energized and will automatically open when deenergized, while the switch 82 automatically 35 closes when its actuating magnet 84 is deenergized and will be opened when energized. These magnets are operated by a low voltage electrical current, the magnet 83 being in a normally closed circuit 85 and 40 the magnet 84 in a normally open circuit 86. Thus in the normal position of parts the circuit 79 may be closed by operation of the push button switch 80, which will energize the magnet 78 and close the electro-magnetically 45 operated motor switch 77, starting the motor 13. The closing of the switch 77 establishes, through one of its blades 77^a, a circuit 87 which shunts out the switch 80, but includes a normally closed push button 50 circuit breaking switch 88 and the switch 34. There is also established a circuit 87^a in shunt with the switch 34 and including a switch 89 mounted on the main shaft 10 of the machine and adapted to open only in 55 one position of angular adjustment of said shaft. The electric motor 36 is supplied with current from the same leads 73, 74, 75, through an electro-magnetically operated switch 90 having its actuating magnet 91 60 in a circuit 92, which includes in series the normally opened switch 35 and the normally closed switch 35^a. A shunt 93 around the switch 35, but including the switch 35^a, is closed by the closing of the switch 90 65 through one blade 90^a thereof so that such

switch will remain closed after the opening of the switch 35. There is also a switch 94 in the circuit 92 in series with the switches 35 and 35^a, said switch 94 being mounted upon the main shaft 10 of the machine to 70 be closed only through a limited angle in the rotation of said shaft. The brake solenoid 13^a is included in the circuit 95 between the leads 73 and 74 when the switch 77 is closed, and the worm actuating solenoid 41 is in 75 the circuit 92 between the leads 74 and 75 when the switch 90 is closed.

With the circuits just described, the operation of the push button 80 will start the 80 main motor 13, which continues its operation after the push button is released, while the operation of the push button 88 at any time will stop the motor. Also the opening of the switch 34 by the lever 33 will not be effective to open the circuit 87, which maintains the switch 77 closed until the switch 89 is also opened, this occurring only at a 85 definite point in the cycle of the tuft setting mechanism. Thus the timing of the opening of the switch 77 is more exact than 90 would be possible through the switch 34 alone. In a like manner the closing of the switch 35 by the lever 33 will establish the circuit 92 of the motor 36, which will be maintained closed after said switch 35 is 95 again opened, but the closing of the switch 35 is not effective until the switch 94 is also closed, this occurring at the completion of the tuft setting cycle when further movement of the tuft setting mechanism is arrested. The switch 35^a, when opened by 100 the lever 33^a, breaks the circuit for the motor 36 and also that for the solenoid 41.

In the commercial manufacture of brushes it is desirable to stop operation of the machine 105 instantaneously in case something goes wrong, thereby avoiding the wasting of material. For instance, if the wire for forming the staples should break or become tangled, the continued operation of the machine would form and deposit tufts, but without securing the same with staples. Again, if the workman is careless and fails to place the work-holding clamps in full 110 engagement with the work holders, proper registration would not be secured and the product would thus be spoiled. To avoid such waste, I have provided various controls which instantaneously stop the machine 115 when anything is abnormal.

These controls are operated by the low voltage circuits 85 and 86, the former being normally closed and the latter normally open. As has been described, the closed circuit 85 energizes the magnet 83, which holds the switch 81 closed and upon the breaking of the circuit 85 the switch 81 will automatically open, thereby causing the opening of the switch 77 for the motor 13. On the other hand, the circuit 86, which is nor- 120 125 130

mally open, if at any time closed, will energize the magnet 84, which will open the switch 82, this also causing the opening of the switch 77 for the motor 13. The circuit 5 85 includes a portion of the wire which is fed to the staple forming mechanism, and therefore, if this wire breaks, the circuit 85 will be automatically opened, which will stop the motor 13. As shown in Figure 11, 10 both circuits 85 and 86 are supplied with low voltage current from the transformer 97, one low voltage terminal being grounded at 98. The circuit 85, after including the magnet 83, leads to a contact finger 99 mounted 15 on an insulated support and extending to normally bear against the staple wire 100, this forming the other ground of the circuit. Thus as long as the wire is being fed the circuit is complete, but if the wire 20 breaks and moves out of contact with the finger 99, this will open the circuit 85, deenergizing the magnet 83 and permitting the opening of the switch 81, which, deenergizing the magnet 78, opens the switch 77 25 of the motor 13. The circuit 86, after including the magnet 84, extends to various parts of the machine, where any abnormal condition will close a ground. One of these parts is a tube 101, which surrounds the 30 staple feed wire 100, but is out of electrical contact therewith. Thus during the normal operation of the machine the circuit 86 will remain open, but if the wire clogs and buckles within the tube 101, this will close 35 the ground, which, by energizing the magnet 84, opens the switch 82, deenergizing the magnet 78 and opens the switch 77 of the motor 13. Another part of the machine controlling the circuit 86 is in connection with 40 the work holders 6 and 6^a. As has been described, the work holding heads 63 of the brush backs are exchanged after each large cycle of the machine, being withdrawn and reinserted into the slideways 62. If the operator fails to press these heads into full engagement with the holders so that the brush backs will be out of registration, this will 45 automatically close the circuit 86, so that it will be impossible to start the motor 13. 50 As shown in Figure 11, the work holders 6 and 6^a have mounted thereon the ground closing switches 102. These are so constructed that when the head 63 is in full engagement with the holder the switch will 55 be opened, but if the head is even a small fraction of an inch from its seat the switch 102 will be closed, thereby preventing starting of the motor 13. It is obvious that similar switches may be placed at various points 60 in the machine, where any lack of operative condition will close the circuit 86 and render the motor closing circuits inoperative.

What I claim as my invention is:

1. In combination, tuft setting mecha-

nism, a work holder for presenting brush backs thereto, driving mechanism for said work holder timed relative to the tuft setting mechanism and including cams for imparting step-by-step movements to said work holder, and means adjustably controlled from said cams to return the work holder to its initial position after a predetermined number of steps. 65

2. In combination, tuft setting mechanism, a work holder for presenting brush backs thereto, driving mechanism for said work holder timed relative to the tuft setting mechanism and including a cam for imparting step-by-step movements to said work holder, means for stopping said tuft setting 75 mechanism at the completion of said step-by-step movements, means for disconnecting said cam from said driving mechanism, and means for completing the cycle of said cam to return the same to its initial position 80 while said tuft setting mechanism is inactive. 85

3. The combination of tuft setting mechanism, a work holder for presenting brush backs thereto, driving mechanism between 90 said tuft setting mechanism and work holders, including cams for imparting step-by-step movements to said work holder corresponding to the number of tufts to be set, means for arresting movement of said timed 95 driving mechanism at the completion of the setting of said tufts, and automatic means operating after the stopping of said mechanism for completing the cycle of the cam to restore the same to its initial position prior 100 to a subsequent operation of said tuft setting mechanism. 105

4. The combination of tuft setting mechanism, a work holder for presenting brush backs thereto, driving mechanism timed with 105 relation to said tuft setting mechanism including cams for imparting step-by-step movements to said work holder corresponding to the number of tufts to be set, means operating at the completion of the setting of 110 the tufts for disengaging said timed mechanism from said cams, means for independently driving said cams to complete the cycle thereof and means for reengaging said driving mechanism with the cam in its initial position. 115

5. The combination with a tuft setting mechanism and a work holder for presenting brush backs thereto, of driving mechanism timed with relation to said tuft setting mechanism including cams disengageable from 120 said driving mechanism for imparting step-by-step movements to said work holder corresponding to the number of tufts to be set, means actuated at the completion of the setting of the tufts for disengaging said drive mechanism from said cams, an independent motor and connecting mechanism for driv- 125

ing said cams to complete the cycle thereof, and means actuated when said cams have reached their initial position for stopping said independent motor and reengaging said 5 timed driving mechanism with said cams.

6. The combination with tuft setting mechanism and a work holder for presenting brush backs thereto, of cams for imparting step-by-step movements to said work holder, two independent motors, one operating to drive said tuft setting mechanism and the other to drive only said cams, mechanism timed with relation to said tuft setting mechanism and disengageable with said cams 10 whereby the cam is moved one step for each tuft set, controlled means operating during a predetermined step of said cams for stopping said tuft setting motor and mechanism driven thereby, and for disconnecting said 15 mechanism from said cam and starting said cam motor to complete the cycle of the cam, and means operating at the completion of said cycle for stopping said cam motor and reengaging said connecting mechanism with 20 said cam.

7. The combination with tuft setting mechanism and a work holder for presenting brush backs thereto, of cams for imparting step-by-step movements to said work holder, two independent electric motors, the one for driving said tuft setting mechanism and the other for driving only said cams, mechanism timed with respect to said tuft setting mechanism and disengageable from said cams 30 whereby said cam is moved one step for each tuft set, an electro-magnetic brake for said tuft setting motor and mechanism driven thereby, and means operating during the last step movement of the cam for energizing 35 said electro-magnetic brake, means simultaneously operated for energizing said cam driving motor and for electro-magnetically disengaging said connecting mechanism from said cam, and means operating at the 40 completion of the cycle of said cam for de-energizing said cam motor and electro-magnetic means to permit reengagement of said connecting mechanism with said cam.

8. The combination with tuft setting mechanism and a work holder for presenting brush backs thereto, of timed connecting mechanism between said tuft setting mechanism and work holder including a cam shaft, a cam carrier longitudinally adjustable on 50 said shaft and a series of cams on said carrier adjusted by the movement of the same into alternative engagement with said work holder.

9. The combination with a tuft setting mechanism and a work holder for presenting a brush back thereto, of timed connecting mechanism between said tuft setting mechanism and work holder including a hollow cam shaft, a cam carrier slidably mounted 55 on said cam shaft, a series of cams mounted

on said carrier, an adjusting screw extending within said hollow cam shaft and operable from the end thereof, and a nut engaging said screw having a connection extending through a slot in the cam shaft to said 70 carrier, whereby the latter may be adjusted to bring any predetermined cams into engagement with said work holder.

10. The combination with tuft setting mechanism and a work holder for presenting brush backs thereto, of a continuously operating cam for imparting a step-by-step movement to said work holder, timed connecting mechanism between said tuft setting mechanism and cam, whereby the intervals of 75 rest of said work holder correspond to the tuft setting operations on the work, and a variable speed element in said connecting mechanism for retarding movement of said cam during the rest intervals of the holder 80 and for accelerating the cam during the remainder of its movement.

11. The combination with tuft setting mechanism and a work holder therefor, of a motor for operating said tuft setting mechanism, an electro-magnetic brake for stopping said motor and mechanism driven thereby, a series of cams for alternatively operating said work holder and imparting thereto step-by-step movements, timed mechanism between said tuft setting mechanism and said cams including a worm wheel on the cam shaft and a worm in mesh with said worm wheel, electro-magnetically operated means 90 for disengaging said worm from said worm wheel, a motor for independently driving said worm wheel and cams when said worm is disengaged therefrom, circuit opening and closing switches for the circuits of said motors and other electro-magnetically operated devices, a trip member adjustably secured to said worm wheel in positions corresponding to the steps of the different cams for actuating said circuit closing and opening switches to stop said tuft setting motor 100 and to apply the brake thereto at the completion of the step-by-step movement of the cam and to simultaneously disengage said worm from said worm wheel and energize the independent motor, and a second trip 105 for opening the circuit of said independent motor at the completion of the cycle of said cam.

12. The combination with tuft setting mechanism and a work holder therefor, of 110 connecting mechanism therebetween including a rotary cam having a plurality of equally timed steps for imparting intermittent movements to the holder, each step corresponding to one cycle of the tuft setting mechanism and all of said steps constituting less than a full cycle of the cam, and means operating at the completion of the stepped movements of the cam for stopping said 115 tuft setting mechanism, means operating to 120

125

130

disconnect the cam from said tuft setting mechanism, independent means for continuing the rotation of the cam to complete the cycle thereof, and means for stopping and overcomes inertial torque of the cam and for then reestablishing the timed connection with the tuft setting mechanism.

13. In a brush machine, the combination of tuft setting mechanism, a work holder for presenting brush backs thereto, driving mechanism for said work holder timed relative to said tuft setting mechanism, a cam included in said driving mechanism adapted to impart a step-by-step movement to said work holder, means for automatically operating said cam independently of said tuft setting mechanism after a predetermined step-by-step movement thereof and means for automatically stopping the independent

operation of said cam after a predetermined movement thereof.

14. In a brush machine, the combination of tuft setting mechanism, a work holder for presenting brush backs thereto, a rotary cam having a plurality of stepped portions extending for less than a full cycle of the cam, mechanism operated by said cam for positioning the work holder relative to said tuft setting mechanism, means for driving said cam in timed relation to said tuft setting mechanism for a predetermined portion of the cycle, means for driving said cam independently of said tuft setting mechanism for the remainder of the cycle and automatic control means for alternately operating the driving means aforesaid.

In testimony whereof I affix my signature.
CONRAD JOBST
